Primary Examiner — Angela J Lee*Assistant Examiner* — Anthony Vincent Rotolo(57) **CLAIM**

The ornamental design for a decorative wire frame, as shown and described.

DESCRIPTION

FIG. 1 is a front, right and top perspective view of a decorative wire frame showing my new design; FIG. 2 is a rear, left and bottom perspective view thereof; FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view thereof shown in an environment of use.

The broken lines in FIG. 9 are for the purpose of illustrating environmental subject matter that form no part of the claimed design.

1 Claim, 9 Drawing Sheets(56)
